Primary Examiner — W. A. Teddy Falloway*(74) Attorney, Agent, or Firm* — Mintz, Levin, Cohn, Ferris, Glovsky and Popeo, P.C.(57) **CLAIM**

The ornamental design for a vaporizer cartridge packaging, as shown and described.

DESCRIPTION

FIG. 1 is a top, front, and left side perspective view of a vaporizer cartridge packaging of our design;

FIG. 2 is a top view thereof;

FIG. 3 is a bottom view thereof;

FIG. 4 is a front view thereof;

FIG. 5 is a rear view thereof;

FIG. 6 is a left side thereof; and,

FIG. 7 is a right side view thereof.

The long-dashed broken lines illustrate perforations of the vaporizer cartridge packaging that form a part of the claimed design.

1 Claim, 5 Drawing Sheets(56)
